RAILWAY TIE PLATE

George T. Willard, St. Louis, Mo.

Application August 27, 1934, Serial No. 741,559

9 Claims. (Cl. 238—283)

This invention relates to railway tie plates. An object of the invention is to provide an improved railway tie plate equipped with means for resiliently holding the rail on the plate by the application of yielding pressure against the outer vertical face of the rail base flange to eliminate or retard creeping of the rail without rigidly attaching the rail and the plate together. It is desirable to avoid rigid connection of the rail with the plate because where such rigid connection is provided, there is a tendency to lift the tie from its bed by the wave motion of the rail under rolling load.

Tie plates embodying this invention may be rigidly attached to the ties by any appropriate fastening means, such as screw spikes or bolts, which reduce mechanical wear on the ties.

My novel and improved connecting means for resiliently connecting the rail and the tie plate exerts pressure in a horizontal direction against the rail base flange and may also embody means for yieldingly bearing on the upper surface of the rail base flange to retard or limit the upward vertical movement of the rail relatively to the tie plate during wave motion of the rail under rolling load. This connecting means for resiliently holding the rail on the plate is preferably held under tension by an adjustable holding device provided for that purpose.

The resilient connecting means for holding the rail on the tie plate is movable vertically with the rail but is substantially held against horizontal movement with the creeping of the rail by lugs or shoulders formed on the upper surface of the tie plate adjacent to the edge of the rail base and these lugs or shoulders may be formed integrally with the tie plate in the rolling of the tie plate or during the finishing process.

While the resilient connecting means between the tie plate and the rail is movable vertically with the rail, nevertheless said connecting means holds the rail under downward pressure as well as horizontal pressure. When the connecting means is used on only one side of the rail base flange, the opposite edge of the rail base flange will be in cooperative relation to a shoulder rising above and extending over to overhang the rail base flange but spaced therefrom to allow the free vertical movement of the rail wave motion under rolling loads.

Other objects and advantages of the invention will be apparent from the following description, reference being made to the annexed drawing, in which—

Fig. 1 is a perspective view of a tie plate and rail engaging means embodying my invention.

Fig. 2 is a top plan view of the tie plate and rail engaging means, the web of the rail being in section.

Fig. 3 is a vertical cross sectional view on the line 3—3 of Fig. 2 of the tie plate showing the resilient connecting means in one useful relationship to the tie plate and the rail base flange.

Fig. 4 is a similar vertical cross sectional view of the tie plate showing the resilient connecting means in another useful relationship relatively to the tie plate and the rail base flange.

In the embodiment of the invention chosen for illustration, a tie plate 1 is formed with a seat 2 between transverse shoulders 3 and 4 upon which may be placed a cushion 5; or said cushion 5 may be omitted, if desired. The tie plate is formed with holes 6 for the reception of screw spikes or bolts 7 for fastening the tie plate on the tie 8.

The rail base 9 may be seated on the cushion 5, when said cushion is used; or may be seated directly on the seat 2 when the cushion is omitted. In the illustrated form of the invention, the shoulder 3 is formed with a laterally extended marginal portion 10 which projects above the adjacent marginal portion of the base 9 and functions to prevent the rail from overturning.

My improved resilient connecting means in the form of a spring clip is designed to exert a lateral tension against the vertical face of the rail base flange 9, which will prevent the rail from creeping; and is also designed to exert a lesser downward pressure or tension on the top of the rail base to retard the wave motion and stiffen the track structure. The lateral and downward pressures may be varied in tension by an adjustable nut or by varying the thickness of the spring clip to obtain a semi-rigid construction as required by the conditions of use. This improved connection between the tie plate and the rail eliminates or minimizes the churning of the ballast and the consequent shattering of the ties, which destructive effects are incident to the use of tracks in which the rails are rigidly attached to the tie plates and to the ties.

As shown in Fig. 3 of the drawing, the spring clip has one end 11 seated upon the marginal portion of the rail base 9 and a portion 12 exerting a lateral pressure or tension against the adjacent vertical face 13 of said rail base, the opposite end portion 14 of the clip being engaged in a hole 15 in the tie plate 1 and supported by a shoulder 16 on the clip seating on the upper surface of the tie plate. A bolt 17 extends through a hole 18 in

the tie plate 1 and through an elongated hole 19 in the spring clip and securely holds the spring clip in the relation shown and described. The tension of the spring clip may be varied by varying the position of the nut 20 on the bolt, as should be apparent by reference to the drawing.

The cushion 5, shown in Fig. 3 of the drawing, absorbs wheel shocks, reduces maintenance costs and prolongs the life of the ties and the metal parts while deadening or minimizing noise and obtaining smoother riding track. In this arrangement, the end of the spring clip 11 engages the rail base but does not seat upon the upper surface of the tie plate. The spring clip extends through a notch 22 in the shoulder 4 and is thereby held from displacement. Obviously the spring clip ends 14 and 16 may be held in place otherwise than as shown, as by abutments on the top of the tie plate, or by an auxiliary shouldered rigid clip fitting over the bolts 17 and 29, or otherwise as desired.

In the relationship of the parts shown in Fig. 4, the cushion 5 is omitted, the end portion 23 of the spring clip extends over but does not seat against the upper surface of the marginal portion of the rail base 9, being separated therefrom by a slight space 24. The portion 25 of the spring clip exerts a lateral tension against the vertical face 13 of the rail base and seats upon the upper surface of the tie plate 1 in the notch 22. The opposite end portion 26 of the spring clip extends into a hole 27 in the tie plate and is supported by a shoulder 28 seating on the tie plate. The bolt 29 extends through the hole 18 in the tie plate and through a hole 30 in the clip, corresponding to the hole 19, and is equipped with a nut 31, whereby the tension and pressure of the spring clip may be varied, as desired.

It should now be apparent that this invention attains all of its intended objects and purposes efficiently and satisfactorily and that the invention may be varied within the scope of equivalent limits without departure from the nature and principle thereof.

45 I claim:

1. The combination of a tie plate having a rail seat and having a hole spaced laterally from the rail seat, a railway rail having a base flange extending across said seat, a spring clip having one end portion engaging the outer vertical face of said rail base flange and having a remaining extended end portion engaging the upper surface of said flange and having the other end portion engaging the wall of said hole that is farthest from said base flange, a bolt device having its lower end detachably interlocked with said tie plate between said end portions of said clip and having its upper end extending through said clip and holding said clip under tension to exert pressure laterally against said vertical face of said rail base flange, and parts integral with said plate between said bolt device and said base flange holding said clip from lateral displacement.

2. The combination of a tie plate having a rail seat and having a hole provided with a wall spaced laterally from the rail seat, a railway rail having a base flange extending across said seat, a resilient member having near one end a portion engaging against the outer vertical face of said rail base flange and another portion extending over the margin of said flange and having its opposite end portion engaging against said wall of said hole, and said member having a hole between said end portions thereof, a fastening device having its lower end interlocked with said tie plate be-

tween said end portions of said resilient member and having its upper end extending through said hole in said resilient member and holding said member under tension to exert pressure laterally against said vertical face of said rail base flange, and a shoulder on the resilient member seating on said tie plate beyond said hole for supporting said second end portion of said resilient member upon said tie plate.

3. The combination of a tie plate having a rail seat and having a hole provided with a wall spaced laterally from the rail seat, a railway rail having a base flange extending across said seat, a resilient member having near one end a portion engaging against the outer vertical face of said rail base flange and another portion extending over the margin of said flange and having its opposite end portion engaging against said wall of said hole, and said member having a hole between said end portions thereof, a fastening device having its lower end interlocked with said tie plate between said end portions of said resilient member and having its upper end extending through said hole in said resilient member and holding said member under tension to exert pressure laterally against said vertical face of said rail base flange, and parts integral with said tie plate between said fastening device and said base flange limiting lateral movement of said rail and holding said resilient member from lateral displacement.

4. The combination of a tie plate having a rail seat and a hole provided with a wall spaced laterally from the rail seat, a railway rail having a base flange extending across said seat, a spring clip engaging the edge of the rail base and having one end extending over the margin of said base flange and having the other end engaging the wall of said hole that is farthest from said flange, a shoulder integral with said spring clip seating on said tie plate beyond said hole for supporting said spring clip, and a fastening device extending through said spring clip and having its lower end interlocked with said plate between the ends of said spring clip and adapted to exert vertical pressure against said spring clip, the contour of the spring clip translating said pressure into lateral pressure against the edge of the rail base.

5. The combination of a tie plate having a rail seat and a hole provided with a wall spaced laterally from the rail seat, a railway rail having a base flange extending across said seat, a spring clip engaging the edge of the rail base and having one end extending over the margin of said base flange and having the other end engaging the wall of said hole that is farthest from said flange, a shoulder integral with said spring clip seating on said tie plate beyond said hole for supporting said spring clip, a fastening device extending through said spring clip and having its lower end interlocked with said plate between the ends of said spring clip and adapted to exert vertical pressure against said spring clip, the contour of the spring clip translating said pressure into lateral pressure against the edge of the rail base, and a shoulder integral with said tie plate extending over the opposite margin of said base flange.

6. The combination of a tie plate having a rail seat and a hole spaced laterally therefrom, a railway rail having a base flange extending across said seat, a resilient member engaging the edge of the rail base and having one end extending over said base flange and having the opposite end engaging the wall of said hole that is farthest

- from said base flange, means for supporting said last named end of said resilient member on said tie plate, a clamping device extending through said resilient member and having one end interlocked with said tie plate between said base flange and said hole and adapted to exert vertical pressure against said resilient member, the contour of said member translating said pressure into lateral pressure against the edge of the rail base, 5 and a shoulder integral with said tie plate engaging the opposite margin of said base flange.
7. The combination of a tie plate having a rail seat, a railway rail having a base flange extending across said seat, a shoulder engaging one 10 edge of said flange, a spring clip having one end engaging the opposite edge of said flange and having its opposite end engaging said tie plate, said spring clip having a hole therethrough intermediate of its ends, parts integral with said tie 15 plate limiting lateral movement of said rail and preventing lateral movement of said spring clip, a bolt extending through said hole and having its lower end interlocked with said tie plate between the ends of said spring clip, and a nut screwed 20 upon the upper end of said bolt and adapted to exert vertical pressure against said spring clip, the contour of said clip translating said pressure into lateral pressure against the edge of the rail base, 25
- 25 upon the upper end of said bolt and adapted to exert vertical pressure against said spring clip, the contour of said clip translating said pressure into lateral pressure against the edge of the rail base, and parts 30 integral with said plate between said bolt and said base flange holding said rail and said spring clip from lateral displacement.
8. The combination of a tie plate having a rail seat, a railway rail having a base flange extending across said seat, a shoulder engaging one edge of said flange, a spring clip having one end engaging the opposite edge of said flange and

having its opposite end engaging said tie plate, said spring clip having a hole therethrough intermediate of its ends, a bolt extending through said hole and having its lower end interlocked with said tie plate between the ends of said 5 spring clip, a nut screwed upon the upper end of said bolt and adapted to exert vertical pressure against said spring clip, the contour of said clip translating said pressure into lateral pressure against the edge of the rail base, and parts 10 integral with said plate between said bolt and said base flange holding said rail and said spring clip from lateral displacement.

9. The combination of a tie plate having a rail seat, a railway rail having a base flange 15 extending across said seat, a shoulder integral with said tie plate having a portion extending over one margin of said base flange, a spring clip engaging the opposite edge of said base flange and having one end extending over the opposite 20 margin of said base flange and having its opposite end abutting against and supported by said tie plate, a bolt extending upwardly through said spring clip and having its lower end interlocked with said tie plate between the ends of 25 said spring clip, a nut screwed upon the upper end of said bolt and adapted to exert vertical pressure against said spring clip, the contour of said clip translating said pressure into lateral pressure against the edge of the rail base, and 30 means holding said rail and said spring clip from lateral displacement.

GEORGE T. WILLARD.
